ELECTRIC SWITCH

Ralph A. Millermaster, Milwaukee, Wis., assignor
to Cutler-Hammer, Inc., Milwaukee, Wis., a cor-
poration of Delaware

Application March 28, 1932, Serial No. 601,525

18 Claims. (Cl. 200—50)

This invention relates to improvements in electric switches, and more particularly to enclosed or safety switches of the fused type.

An object of the invention is to generally improve and simplify the construction, assembly and operation of switches of the aforementioned character.

Another object is to provide novel and improved means for carrying and operating the movable contacts of the switch.

Another object is to provide a fused safety switch wherein the parts are so arranged as to permit use of an enclosing casing of minimum depth.

Another object is to provide an arrangement whereby the movable switch parts may be assembled with respect to the casing entirely independently of the other parts of the switch.

Another object is to provide a novel form and arrangement of the stationary contacts and terminal elements of the switch whereby said elements may be removed and replaced without disturbing the other parts of the device.

Another object is to provide a novel form of fuse chamber for the device.

Another object is to provide novel means for controlling access to said fuse chamber.

Other objects and advantages of the invention will hereinafter appear.

The accompanying drawings illustrate an embodiment of the invention which will now be described, it being understood that the embodiment illustrated is susceptible of modification in certain details thereof without departing from the scope of the appended claims.

In the drawings, Figure 1 is a plan view of a fused safety switch constructed in accordance with my invention,—the main cover member thereof being shown in fully opened position.

Fig. 2 is a sectional view on the broken line 2—2 of Fig. 1.

Fig. 3 is a sectional view, on the line 3—3 of Fig. 1.

Fig. 4 is a perspective view of the movable parts of the switch shown in Figs. 1, 2 and 3, and illustrating the manner in which said parts may be assembled.

Fig. 5 is a fragmentary sectional view, on the line 5—5 of Fig. 1, showing the latching means for releasably holding the sliding plate in one of its extreme positions.

Fig. 6 is a perspective view of one of the duplicate molded insulating members which jointly provide a partial enclosure for the fuse receptacles of the device.

Fig. 7 is a plan view of the switch operating handle prior to attachment thereof to the shaft, and

Fig. 8 is a similar view of the handle at right angles to the view of Fig. 7.

Referring to the drawings, the numeral 10 designates in general a relatively shallow box-like sheet metal casing having a bottom wall 11, side walls 12 and 13 and end walls 14 and 15,—the end wall 15 being preferably of the removable or "snap-in" type, as indicated by the formation of the flanges at 16 in Figs. 2 and 3, nut and bolt devices 17 being preferably provided to rigidly secure said end wall in position. Said casing is also provided with an openable cover 18, which as shown is of flat formation and hinged to the casing at 19 and 20 (Fig. 1).

The side wall 12 of the casing is provided with a circular opening 21 (Fig. 4) of a size to permit ready insertion of and to provide a bearing for 75 one end of the shaft 22, which as shown is of square cross section throughout the major portion of the length thereof,—the forward end of said shaft being of reduced cylindrical cross section (as shown at 23 in Figs. 1 and 4) to fit 70 within an alined circular bearing opening of proper size provided in the side wall 13.

Shaft 22 is provided with a one-piece stamped sheet metal handle 24 of the form best illustrated in Figs. 7 and 8. The flat lower end portion of 85 said handle is provided with a square opening 25 which is adapted to fit snugly onto the square shaft 22 in a relation flush with one end of the latter, as shown in Figs. 1 and 4. The handle 24 is then welded to shaft 22 at points intermediate the four flat sides of the latter, as indicated at 26 in Fig. 4, whereby said parts are rigidly and permanently united to each other. This arrangement of the weld-spots 26 permits 90 positioning of the lower portion of handle 24 flush against one side of a washer 27 which is strung upon shaft 22,—the other side of said washer being positioned against the outer surface of side wall 12. A washer 28 is strung upon shaft 22 and adapted to lie against the inner 95 surface of wall 12,—said shaft being provided with a transverse opening 29 to receive a cotter pin 30 or other securing element whereby the shaft 22 is held in assembled relation to the metal casing.

Prior to insertion of cotter pin 30, however, a punched and stamped sheet metal member 31 is strung upon shaft 22, said member having a square opening to provide an interlocking connection between the same and said shaft, and 110

said member having its free end portion 31^a of reduced width and bent on a slight bias to extend laterally in a plane at right angles to the plane of the body portion thereof. Member 31 provides an interlocking connection between shaft 22 and a movable part of the casing, as herein-after described.

Also slidable onto shaft 22 is a tube 32 of square cross section whereby the latter is interlocked with the former for rotation thereby. Tube 32 is formed of insulating material preferably of the phenol formaldehyde condensation type sold commercially under the trade name of "bakelite". Slidable onto tube 32 in the manner illustrated in Fig. 4 are the cylindrical molded insulating members 33, 34 and 35 and the flat punched sheet metal contactors 36 and 37,—member 33 having an end recess to receive the circular body portion 36^a and portions of the radial arms 36^b, 36^c in a substantially flush relation and to permit a slight amount of lateral movement of said contact arms relatively to said member. Member 34 is provided with a similar end recess to accommodate the corresponding parts of contactor 37.

The aforementioned cylindrical insulating members and the contactors are provided with square openings or passages whereby the same are interlocked with tube 32 for rotation or oscillation thereby. As best illustrated in Fig. 2 the longitudinal center lines of the radial arms 36^b, 36^c of contactor 36 are spaced apart through an arc of substantially one hundred thirty-seven degrees,—and the centrally located square opening in the contactor is so arranged that two of the sides of said opening are in planes parallel to the longitudinal center line of arm 36^c. In this connection it will be noted from Fig. 7 that the walls of the square opening 25 in handle 24 are so arranged angularly with respect to the walls of the openings in contactors 36 and 37 as to insure predetermined angular positions of the arms of the contactors upon movement of said handle to opposite extreme positions. Contactors 36 and 37 are of identical form, and the same are arranged in like relation to shaft 22.

Insulating member 34 is adapted to retain contactor 36 within the end recess of member 33, and member 35 is provided to retain contactor 37 within the end recess of member 34. The non-adjacent edges of the contactor arms are chamfered or beveled, as indicated at 36^d, 36^e and 37^d, 37^e in Fig. 4, to facilitate engagement thereof with resilient stationary contacts of reflexed form. Said contacts are designated by the numerals 38, 39, 40 and 41 and the same are of identical form with respect to each other. The contacts 38 and 40 are secured to an insulating base member 42 which is in turn secured to the bottom wall 11 of the casing as by means of a pair of screws 43 and 44.

The manner of attaching the contact 38 to base 42 is best illustrated in Figs. 1 and 2, wherein I have shown a bus member having an angled end portion 38^a to which the contact is rigidly secured as by means of a rivet 38^b. The other end 38^c of said bus member is adapted to overlie the ledge portion 42^a formed on base 42, said portion as shown having an opening therethrough to provide clearance for a screw 42^b the head of which is located within a countersink in the lower surface of said base,—said screw head being restrained against longitudinal movement within said countersink as by means of a quantity

of wax or cement 42^c. Threaded onto the shank of screw 42^b is a nut 42^d which acts to clamp bus member 38^c and contact 38 in position,—said contact being located within a recess 42^e and restrained by the walls thereof against lateral displacement. Strung upon the shank of screw 42^b is a tubular wiring terminal element 42^f of well known form, said element being clamped in position by means of a nut 42^g.

It will thus be apparent that terminal element 42^f and contact 38 with its associated bus member may readily be removed for repair or replacement by merely removing the nuts 42^g and 42^d without disturbing any of the other parts of the device. The facility with which the stationary contact and terminal members may be removed and replaced is of importance from a practical viewpoint. The contact 40 and its associated terminal element are secured to base 42 in a like manner, as best illustrated in Fig. 1.

Contact 39 as shown in Figs. 1 and 2 is adapted to straddle the outer end of a bus member 45, a wiring terminal member 45^a being superimposed upon the flat portion of said contact, and a screw 45^b having threaded engagement with member 45 to rigidly clamp contact 39 and member 45^a thereto. A binding screw 45^c has threaded engagement with the offset portion of member 45^a. Bus member 45 is secured to the insulating base member 46 as by means of a pair of screws 47 and 48,—screw 47 having threaded engagement with said bus member and screw 48 being adapted to penetrate said bus member and the flat portion of a fuse clip 49 of known form and engaging a nut 50 to retain said parts in assembled relation. Contact 41 and its associated parts including fuse clips 51, are secured to base 46 in a like manner, as illustrated in Fig. 1.

Base 46 is supported within the metal casing in planes offset upwardly and laterally with respect to the center line of shaft 22. The support therefor preferably comprises a plate 52 to which the same is attached as by means of a plurality of screws 53,—the plate 52 having end flanges 52^a, 52^b whereby the same may be attached to the side walls 12 and 13 of the casing as by means of rivets 54.

Also secured to the base 46 are a pair of terminal bus members 55 and 56 to the inner ends of which are secured the fuse clips 57 and 58 and to the outer ends of which are secured the terminal elements 59 and 60, respectively. Arranged upon base 46 in a manner to partially enclose the longitudinally aligned sets of fuse clips 49, 57 and 51, 58 are a pair of molded insulating members 61 of like form, said members being of substantially U-shape in horizontal cross section, and each is provided at opposite ends thereof with integral lugs 61^a, 61^b which lugs are formed to provide for attachment of said members to said base as by means of screws 61^c the shanks of which take into nuts (not shown) located within countersunk recesses in the bottom surface of base 46. One of the members 61 is shown in perspective in Fig. 6,—the same being provided in the bottom surface thereof with channels 61^d, 61^e to accommodate the bus members associated with the terminal clips 49, 51 or 57, 58 aforescribed. As will be noted the members 61 are arranged with the open ends thereof opposed to but substantially spaced from each other to facilitate removal of fuses (either manually or by means of a suitable tool) from the respective longitudinally aligned sets of clips. Also as will be noted the end wall portions of members 61 are interposed be-

- tween said clips and their respective wiring terminals, said walls extending upwardly from base 46 to a plane substantially flush with the upper edges of the side walls 12 and 13 of the casing. 5
- As shown in Fig. 1, base 42 is provided with a recess or pocket 62 within which are located a plurality of line terminals such as 63, 64 for the neutral wire of a three-wire system; said terminals being electrically connected to a plate or bus member 65 which is secured within said recess as by means of a screw 66. Terminal 64 and a meter-test clip 67 are attached to plate 65 as by means of screw 68. A suitable grounding wire terminal 69 may be attached to the bottom wall 11 of the casing as by means of a screw 70.
- The main body portion of the switch operating handle 24 is offset outwardly from the lower end portion thereof which is attached to shaft 22, 10 and said main body portion is provided with an opening 24^a which is adapted to selectively register with suitably positioned openings (not shown) in a bracket 71 whereby handle 24 may be locked in either of its extreme positions through the medium of a suitable pad-lock (not shown). The bracket 71 may be attached to the side wall 12 of the casing as by means of rivets 71^a. The upper end portion 24^b of handle 24 is bent outwardly at substantially right angles to 15 the main body portion thereof, and said bent end is further bent to segmental form in cross section, as indicated at 24^c in Fig. 7 to provide a proper hand-grip for manipulation thereof.
- The main cover member 18 of the casing is 20 provided with a substantially rectangular opening 72 which is adapted to provide access to the fuse receptacle under certain conditions when said cover is closed,—it being noted that said opening is slightly enlarged at the points 72^a, 72^b to give full effect to the aforescribed spacing of the adjacent ends of insulating members 61 for facilitating removal of fuses from the fuse clips. A plate 73 of greater dimensions than the opening 72 is slidably mounted upon the lower 25 surface of cover 18,—said plate being retained and guided for longitudinal movement into and out of register with opening 72 as by means of a pair of strip metal members 74 and 75,—the opposite ends of which are respectively offset toward the lower surface of cover 18 and riveted thereto as by means of rivets 74^a, 74^b and 75^a, 75^b. Plate 73 is provided at opposite longitudinal edges thereof with downwardly extending flanges 73^a, 73^b which engage the outer edges of members 74 and 75 to insure rectilinear movement 30 of the plate.
- Plate 73 is provided with a pair of openings 73^c, 73^d and the members 74, 75 are provided with inwardly extending bosses or projections 74^c, 75^c adapted to snap into said openings for releasably retaining plate 73 in its upper extreme position as shown in dotted lines in Figs. 1 and 5. Arranged flush with the upper edge of opening 72 and spaced from cover 18 just sufficiently to accommodate the upper edge of plate 73 is a guard member 76, the latter having an offset portion 76^a which is spot welded or otherwise rigidly and permanently secured to the lower surface of said cover.
- Rigidly secured to plate 73 and projecting outwardly through cover 18 is a handle 77,—the cover 18 being provided with a slot 18^a to accommodate handle 77 in the lower extreme position of plate 73, and the latter having an integral lug 73^e to insure closure of slot 18^a in the upper extreme position of said plate. 80
- The flange 73^b of plate 73 is of the special form best illustrated in Fig. 3 whereby the same is adapted for cooperation with the bent end 31^a of member 31 to provide a proper interlocking connection between the plate 73 and the movable parts of the switch. Thus assuming open positioning of the switch contacts (as represented by the dotted line position of the switch operating handle 24 in Fig. 1) and assuming positioning of plate 73 as shown in full lines in Fig. 1, it will be apparent that upon closing of cover 18 the opening 72 therein will be uncovered to provide access to the fuse receptacles. This relative positioning of the parts is shown in Fig. 2,—and as indicated by the relative positions of flange 73^b of plate 73 and the bent end 31^a of member 31, it is not possible to effect closure of the switch contacts pending movement of plate 73 to its upper extreme position, whereupon access to the fuse receptacles is prevented. 90
- In like manner upon closure of the switch contacts, as represented by the relative positions of the parts in Fig. 3, the bent end 31^a of member 31 will be located in the path of flange 73^b to prevent movement of plate 73 to its lower extreme position (wherein access to the fuse receptacles is provided) pending movement of the switch contacts to open position. 100
- As shown in Fig. 1 the side wall 12 of the casing has rigidly attached thereto, as by spot welding, the lower end of a resilient latch member 78 for the cover 18, the latter having an opening 18^a to provide clearance for said latch member. The upper end of member 78 is provided with the usual relatively large and relatively small openings (not shown), the large opening being adapted to receive the hasp of a padlock whereby cover 18 may be locked in closed position, and the small opening cooperating with the loop 18^b sheared and bent upwardly from cover 18 to receive the wire portion of a sealing element of usual form. 110
- The bottom wall 11 of the casing is provided with a pair of keyhole slots 79 at its upper end and a pair of double-keyhole slots 80 at its lower end to facilitate attachment of the casing to a wall or other support as by means of suitable screws. 120
- While I have described the contactors 36, 37 and insulating members 33, 34 and 35 as being clamped in assembled relation to each other, it is to be understood, as aforesigned, that the end recesses in members 33, 34 (as, for instance, the recess 33^a shown in Fig. 4) are of sufficient end-wise depth to permit a slight degree of lateral movement of the contactors 36, 37 therewithin,—thus providing a sort of "floating" support for the latter which renders the same self-aligning to compensate for any inaccuracy in the positioning of the stationary contacts of the switch. 130
- Secured to the bottom wall 11 of the casing in any suitable manner is a substantially rectangular plate 81 of a suitable fibrous insulating material, such as that sold commercially under the trade name of "conite". As shown plate 81 has one end thereof clamped beneath the base 42, the other end of said plate being adapted to underlie the radial arms of the contactors 36, 37 in all positions of the latter to protect the bottom wall 140 11 from any arcs incident to separation of the switch contacts.
- As shown the member 31, tube 32 and the contactors 36, 37 and insulating members 33, 34 and 35 carried by said tube are held in assembled 150

- relation to each other and in a given adjusted position longitudinally of shaft 22 by a pair of substantially U-shaped metal clamps 82 and 83,— said clamps having clearance openings 82^a, 83^a in 5 the upper arms thereof and tapped openings 82^b, 83^b in the lower arms thereof for cooperation with screws 82^c, 83^c. By assembling the clamps 82, 83 upon shaft 22 in the manner illustrated the heads of the screws 82^c, 83^c are readily accessible to 10 provide for removal or replacement of any of the movable parts of the switch upon opening of the cover 18; and, as aforescribed, without disturbing any of the other parts of the device.
- What I claim as new and desire to secure by 15 Letters Patent is:
1. In an electric switch, in combination, an operating shaft of angular cross section, a tubular insulating member of similar cross section slidably mounted upon said shaft, a flat punched sheet metal contactor slidably engaging said insulating member and interlocked therewith for rotation thereby, a pair of molded insulating members arranged on opposite sides of said contact member and adapted to expose the blade portions of the latter, said last mentioned insulating members also having interlocking engagement with said first mentioned insulating member; and clamping means for restraining said parts from substantial movement longitudinally 20 of said shaft.
2. In an electric switch, in combination, an operating shaft of substantially rectangular cross section throughout the major portion of the length thereof, a lever secured to one end of said shaft, a tubular member formed of insulating material of the phenol-formaldehyde condensation type, said insulating member being of rectangular cross section to slidably engage said shaft and to interlock therewith for rotation thereby, a plurality of flat punched sheet metal contactors and a plurality of molded insulating members arranged on opposite sides of and between said contactors, said contactors and said last mentioned insulating members having rectangular 25 openings to provide for sliding engagement and interlocking thereof with said first mentioned insulating member, all of said parts being simultaneously adjustable longitudinally of said shaft, and a pair of clamping devices engaging said shaft and arranged at opposite ends of said parts to retain the latter in adjusted position with respect to said shaft.
3. In an electric switch, in combination, an operating shaft of substantially rectangular cross section throughout the major portion of the length thereof, a one-piece stamped sheet metal actuating lever having a rectangular opening formed therein to snugly fit over said shaft in a relation substantially flush with one end of the latter, said lever being welded to said shaft at points intermediate the width of the four flat sides of the latter whereby said parts are rigidly and permanently united to each other, a sheet metal casing having a circular opening in one side wall thereof to accommodate said shaft and to provide a bearing for the rectangular portion thereof adjacent to said lever, a washer strung upon said shaft and arranged against the outer surface of said side wall and against the inner 30 surface of said lever, a second washer strung upon said shaft and arranged against the inner surface of said side wall, said shaft having a transverse passage located in a plane adjacent to the inner surface of said last mentioned washer, a removable element penetrating said passage and adapted to 35 maintain said shaft in assembled relation to said bearing opening, the other end of said shaft having a reduced end of cylindrical contour, and the other side wall of said casing having a circular opening alined with said first mentioned opening and adapted to provide a bearing for the last mentioned end of said shaft.
4. In an electric switch, in combination, a box-like sheet metal casing having alined bearing openings formed in opposite side walls thereof, an operating shaft of rectangular cross section insertable into said casing through one of said bearing openings, a punched and stamped sheet metal member having a rectangular opening and a tubular insulating member of rectangular cross 40 section to be strung sequentially upon said shaft, said sheet metal member being adapted to provide a releasable interlocking connection with one of the casing parts, a plurality of molded insulating cylinders and a plurality of punched sheet metal contactors interposed therebetween and spaced thereby, each of said cylinders and said contactors having a rectangular opening therethrough to provide for interlocking engagement thereof with said insulating tube, all of said parts being normally adjustable as a group longitudinally of said shaft to bring the same into registry with other parts of the switch, a pair of clamping devices engaging said shaft at opposite 45 ends of said group of parts to restrain the latter against movement longitudinally of said shaft, said shaft having a reduced cylindrical end to engage the other of said bearing openings, and means associated with said shaft to normally prevent longitudinal displacement thereof in either direction with respect to said side walls of the casing.
5. In an electric switch, in combination, a box-like sheet metal casing having alined bearing openings formed in opposite side walls thereof, an operating shaft of rectangular cross section insertable into said casing through one of said bearing openings, a punched and stamped sheet metal member having a rectangular opening and a tubular insulating member of rectangular cross section to be strung sequentially upon said shaft, said sheet metal member being adapted to provide a releasable interlocking connection with one of the casing parts, a plurality of molded insulating cylinders and a plurality of punched sheet metal contactors interposed therebetween and spaced thereby, each of said cylinders and said contactors having a rectangular opening therethrough to provide for interlocking engagement thereof with said insulating tube, all of said parts being normally adjustable as a group longitudinally of said shaft to bring the same into registry with other parts of the switch, a pair of clamping devices engaging said shaft at opposite ends of said group of parts to restrain the latter against movement longitudinally of said shaft, said shaft having a reduced cylindrical end to engage the other of said bearing openings, and means associated with said shaft to normally prevent longitudinal displacement thereof in either direction with respect to said side walls of the casing.
6. In an electric switch, in combination, a box-like sheet metal casing having bottom, side and end walls and an openable cover, a shaft having the major portion of the length thereof of square cross section, said side walls having alined openings to provide for endwise insertion of said shaft

- into said casing for bearing engagement with said openings, a tubular insulating member of square cross section slideable onto said shaft, a plurality of flat punched sheet metal contactors slideable onto said insulating member and interlocked therewith for rotation thereby, a plurality of molded insulating cylinders also interlocked with said insulating member and arranged on opposite sides of and between said contactors to space the latter relatively to each other and to assist in insulating the same, each of said contactors having a pair of arms extending radially beyond said insulating cylinders, an insulating base secured to the bottom wall of said casing, a second insulating base secured within said casing in a plane above the longitudinal center line of said shaft, a plurality of stationary contact and terminal members secured to each of said insulating bases, and means for effecting oscillatory movement of said shaft to bring said contactors into and out of bridging engagement with said stationary contacts.

7. In an electric switch, in combination, a box-like sheet metal casing having bottom, side and end walls and an openable cover, a shaft having the major portion of the length thereof of square cross section, said side walls having aligned openings to provide for endwise insertion of said shaft into said casing for bearing engagement with said openings, a tubular insulating member of square cross section slideable onto said shaft, a plurality of flat punched sheet metal contactors slideable onto said insulating member and interlocked therewith for rotation thereby, a plurality of molded insulating cylinders also interlocked with said insulating member and arranged on opposite sides of and between said contactors to space the latter relatively to each other and to assist in insulating the same, each of said contactors having a pair of arms extending radially beyond said insulating cylinders, an insulating base secured to the bottom wall of said casing, a second insulating base secured within said casing in a plane above the longitudinal center line of said shaft, a plurality of stationary contact and terminal members secured to each of said insulating bases, and means for effecting oscillatory movement of said shaft to bring said contactors into and out of bridging engagement with said stationary contacts.

8. In an electric switch, in combination, a box-like sheet metal casing having bottom, side and end walls and an openable cover, a shaft having the major portion of the length thereof of square cross section, said side walls having aligned openings to provide for endwise insertion of said shaft into said casing for bearing engagement with said openings, a tubular insulating member of square cross section slideable onto said shaft, a plurality of flat punched sheet metal contactors slideable onto said insulating member and interlocked therewith for rotation thereby, a plurality of molded insulating cylinders also interlocked with said insulating member and arranged on opposite sides of and between said contactors to space the latter relatively to each other and to assist in insulating the same, each of said contactors having a plurality of arms extending radially from a common center at an angle of substantially less than one hundred and eighty degrees with respect to each other, an insulating base secured to the bottom wall of said casing in a plane offset laterally with respect to the center line of said shaft, a second insulating base secured within said casing in planes offset upwardly and laterally with respect to said center line, a plurality of stationary contact and terminal members secured to each of said insulating bases, means for effecting oscillatory movement of said shaft to bring said contactors into and out of bridging engagement with said stationary contacts, a plurality of fuse receptacles carried by said second mentioned insulating base, said cover having an opening adapted to register with said fuse receptacles, a sliding plate movable into and out of register with said opening, and means providing a releasable interlocking connection between said shaft and said sliding plate to normally insure against movement of

- the latter out of register with said opening pending movement of said contactors out of bridging engagement with said stationary contacts.
11. In an electric switch, in combination, a box-like sheet metal casing having bottom, side and end walls and an openable cover, a shaft having the major portion of the length thereof of square cross section, said side walls having aligned openings to provide for endwise insertion of said shaft into said casing for bearing engagement with said openings, a tubular insulating member of square cross section slidable onto said shaft, a plurality of flat punched sheet metal contactors slidable onto said insulating member and interlocked therewith for rotation thereby, a plurality of molded insulating cylinders also interlocked with said insulating member and arranged on opposite sides of and between said contactors to space the latter relatively to each other and to assist in insulating the same, each of said contactors having a plurality of arms extending radially from a common center at an angle of substantially less than one hundred and eighty degrees with respect to each other, an insulating base secured 25 to the bottom wall of said casing in a plane offset laterally with respect to the center line of said shaft, a second insulating base secured within said casing in planes offset upwardly and laterally with respect to said center line, a plurality of stationary contact and terminal members secured to each of said insulating bases, means for effecting oscillatory movement of said shaft to bring said contactors into and out of bridging engagement with said stationary contacts, a plurality of fuse receptacles carried by said second mentioned insulating base, said cover having an opening adapted to register with said fuse receptacles, a sliding plate movable into and out of register with said opening, and means 30 providing a releasable interlocking connection between said shaft and said sliding plate to normally insure against movement of the latter out of register with said opening pending movement of said contactors out of bridging engagement with said stationary contacts, said sliding plate and said cover having cooperating parts to releasably latch the former in registering relation to said cover opening independently of the interlocking connection aforementioned.
12. In a fused safety switch, in combination, a relatively shallow box-like sheet metal casing having bottom, side and end walls and a hinged cover, an insulating base supported within said casing and spaced upwardly a substantial distance from the bottom wall of the latter, a plurality of fuse receptacles carried by said base, said cover being flat and having an opening to register with said fuse receptacles, a pair of metal strips secured at opposite ends thereof 55 to the inner surface of said cover, a plate slidably between the inner surface of said cover and said metal strips and guided by the latter for movement into and out of registry with said cover opening, said plate having a pair of openings and said metal strips having bosses formed thereon and cooperable with said openings to releasably latch said plate in registry with said opening in the cover, wiring terminal elements associated with the opposite ends of the 60 respective fuse receptacles and a pair of molded insulating members of substantially U-shape in horizontal cross section, said insulating members providing baffles between the fuse receptacles and said terminal elements and preventing access to 65 the latter through said cover opening, a switch 70 mechanism located within said casing, and means associated with said plate and adapted for interlocking engagement with said switch mechanism to normally prevent circuit closing operation of the latter pending movement of said plate into registry with said cover opening. 80
13. In a fused safety switch, in combination, a box-like sheet metal casing having a flat main cover member hinged thereto, said cover member having a substantially rectangular opening formed therein to provide access to fuses located within said casing, a pair of strip metal members having the end portions thereof offset toward the under surface of said cover member and rigidly secured thereto in parallel relation to each other, a metal plate slidable between said strip metal members and the under surface of said cover member into and out of registry with said opening, said plate having flanges extending downwardly from opposite sides thereof and engageable with the outer edges of the respective strip metal members to be guided by the latter, said plate having a pair of relatively small openings formed therein, and said strip metal members having bosses formed thereon for cooperation with said openings to yieldably latch said plate in one of its extreme positions. 85
14. In a fused safety switch, in combination, a box-like sheet metal casing having a flat main cover member hinged thereto, said cover member having a substantially rectangular opening formed therein to provide access to fuses located within said casing, a pair of strip metal members having the end portions thereof offset toward the under surface of said cover member and rigidly secured thereto in parallel relation to each other, a metal plate slidable between said strip metal members and the under surface of said cover member into and out of registry with said opening, said plate having flanges extending downwardly from opposite sides thereof and engageable with the outer edges of the respective strip metal members to be guided by the latter, said plate having a pair of relatively small openings formed therein, and said strip metal members having bosses formed thereon for cooperation with said openings to yieldably latch said plate in one of its extreme positions. 90
15. In a fused safety switch, in combination, a box-like sheet metal casing having a flat main cover member hinged thereto, said cover member having a substantially rectangular opening formed therein to provide access to fuses located within said casing, a pair of strip metal members having the end portions thereof offset toward the under surface of said cover member and rigidly secured thereto in parallel relation to each other, a metal plate slidable between said strip metal members and the under surface of said cover member into and out of registry with said opening, said plate having flanges extending downwardly from opposite sides thereof and engageable with the outer edges of the respective strip metal members to be guided by the latter, said plate having a pair of relatively small openings formed therein, and said strip metal members having bosses formed thereon for cooperation with said openings to yieldably latch said plate in one of its extreme positions. 95
16. In a fused safety switch, in combination, a box-like sheet metal casing having a flat main cover member hinged thereto, said cover member having a substantially rectangular opening formed therein to provide access to fuses located within said casing, a pair of strip metal members having the end portions thereof offset toward the under surface of said cover member and rigidly secured thereto in parallel relation to each other, a metal plate slidable between said strip metal members and the under surface of said cover member into and out of registry with said opening, said plate having flanges extending downwardly from opposite sides thereof and engageable with the outer edges of the respective strip metal members to be guided by the latter, said plate having a pair of relatively small openings formed therein, and said strip metal members having bosses formed thereon for cooperation with said openings to yieldably latch said plate in one of its extreme positions. 100
17. As an article of manufacture, a flat punched sheet metal contactor for electric switches, said contactor having a body portion of substantially circular contour, a pair of arms extending radially from said body portion, the radial center lines of said arms being spaced from each other by an arc of approximately one hundred and thirty-seven degrees, said body portion having a relatively large substantially square opening formed centrally therein, for cooperation with an oscillatable supporting element of square cross section and one pair of the walls of said opening being arranged in planes parallel to the radial center line of one of said arms. 105
18. As an article of manufacture, a flat punched sheet metal contactor for electric switches, said contactor having a body portion of substantially circular contour, a pair of arms extending radially 110
19. As an article of manufacture, a flat punched sheet metal contactor for electric switches, said contactor having a body portion of substantially circular contour, a pair of arms extending radially 115
20. As an article of manufacture, a flat punched sheet metal contactor for electric switches, said contactor having a body portion of substantially circular contour, a pair of arms extending radially 120
21. As an article of manufacture, a flat punched sheet metal contactor for electric switches, said contactor having a body portion of substantially circular contour, a pair of arms extending radially 125
22. As an article of manufacture, a flat punched sheet metal contactor for electric switches, said contactor having a body portion of substantially circular contour, a pair of arms extending radially 130
23. As an article of manufacture, a flat punched sheet metal contactor for electric switches, said contactor having a body portion of substantially circular contour, a pair of arms extending radially 135
24. As an article of manufacture, a flat punched sheet metal contactor for electric switches, said contactor having a body portion of substantially circular contour, a pair of arms extending radially 140
25. As an article of manufacture, a flat punched sheet metal contactor for electric switches, said contactor having a body portion of substantially circular contour, a pair of arms extending radially 145
26. As an article of manufacture, a flat punched sheet metal contactor for electric switches, said contactor having a body portion of substantially circular contour, a pair of arms extending radially 150

- from said body portion, the radial center lines of said arms being spaced from each other by an arc of approximately one hundred and thirty-seven degrees, said body portion having a relative-
 5 ly large substantially square opening formed centrally therein, one pair of the walls of said opening being arranged in planes parallel to the radial center line of one of said arms, and the non-adjacent edges of the respective arms being cham-
 10 fered to facilitate entry thereof into cooperative engagement with resilient stationary contacts of suitable form.
 17. As an article of manufacture, a fuse baffle wall comprising a molded insulating member of substantially U-shape in horizontal cross section, said member being adapted to partially surround a plurality of receptacles for fuses of the cartridge type, said member having channels in the bottom surface thereof to provide clearance for wiring terminal bus members of suitable form, and lugs formed integrally with said member at opposite ends thereof, said lugs being formed to provide
 15
 20
- for releasable attachment thereof to a suitable support.
 18. In a device of the character described, in combination, an insulating base, a plurality of longitudinally aligned pairs of clips for fuses of the cartridge type secured to said base, wiring terminal bus members secured to the respective clips and projecting longitudinally therefrom, a pair of molded insulating members of like form, each of said insulating members being of substantially U-shape in horizontal cross section, said insulating members being secured to said base with the open ends thereof opposed to but substantially spaced from each other to facilitate removal of fuses from the respective pairs of clips, said insulating members having the end wall portions thereof interposed between said clips and their respective wiring terminals, and said insulating members having channels in the bottom surfaces thereof respectively to accommodate the bus portions of said terminals.
